Patented Aug. 5, 1913.

UNITED STATES PATENT OFFICE.

WENDEL STOREY, OF MILWAUKEE, WISCONSIN.

STRICKLE APPARATUS.

1,069,633.

Specification of Letters Patent.

Patented Aug. 5, 1913.

Application filed February 21, 1913. Serial No. 749,886.

To all whom it may concern:

- Be it known that I, WENDEL STOREY, a citizen of the United States, and resident of Milwaukee, in the county of Milwaukee and 5 State of Wisconsin, have invented certain new and useful Improvements in Strickle Apparatus; and I do hereby declare that the following is a full, clear, and exact description thereof.
- 10 My invention consists in what is herein particularly set forth with reference to the accompanying drawings and pointed out in the claims of this specification, its object being to provide simple, economical and effi- 15 cient longitudinally reciprocative or traverse strickle-apparatus for sharpening and truing up the points of card-clothing on the main and other cylinders of carding-ma- chines, said apparatus being attachable to a 20 carding-machine to operate simultaneously upon the main and doffer cylinders thereof, and the strickle-mechanism is also applicable in connection with the traverse-mechanism of a card-grinder for operation upon card- 25 ing-machine cylinders other than those spe- cifically noted in the foregoing, whereby a saving of labor is effected and the best re- sults attained with the least expenditure of time.
- 30 Figure 1 of the drawings represents an end elevation of adjustable strickle-mechanism in accordance with my invention at- tached to the traveler of a traverse-mechanism that is shown in cross-section; Fig. 2, 35 a partly sectional elevation of said strickle- mechanism and a fragment of said traverse- mechanism therewith in connection with a bearing for the fancy-roller of a carding- machine, parts of the mechanisms being 40 broken away and the section of others of the parts indicated by line 2-2 in Fig. 1; Fig. 3, a side elevation of a fragment of the strickle-apparatus partly broken away and illustrating the substitution of a strickle- 45 board for the strickle-apron, also illustrated, in order to best adapt my strickle-appara- tuss to carding-cylinders of small diameter, and Fig. 4, a front elevation of what is shown in Fig. 3.
- 50 Referring by numerals to the drawings, 5 indicates each of a pair of T shaped plates in connection with a pair of parallel rods 6 to thus form a guide-frame for a slide at- tachable to the traveler of a traverse-mech- 55 anism, the detail of the slide and traverse- mechanism being hereinafter specified.

Guided on the depending shanks of the plates 5 are the longitudinally slotted shanks of similar plates 7 inverse to those aforesaid and suitably held in connection with the lower brace-rod 8 to therewith constitute a vertically adjustable frame. To maintain the last described frame in vertically adjusted position, the slots of the shanks of its end plates are engaged by 60 bolts 9 that extend through the adjacent end plates of the guide-frame aforesaid, and set-nuts 10 are run on the bolts. It is also to be noted that the angle of the apron may be varied by adjusting the arms 11, the 65 stretchers in connection therewith or both.

In pivotal connection with the foot of each end plate of the vertically adjustable frame to extend therefrom in opposite directions are arms 11 in similar connection with 70 slotted brace-straps 12, these straps and said arms being held in adjusted position by means of a set-screw 13 that extends through the slots of said straps into the ad- jacent end plate of the guide-frame.

Engaging the outer end of each arm 11 and a member 14 of a jointed stretcher is a bolt 15 upon which a thumb-nut 16 is run to hold said stretcher in adjusted position, and by means of a bolt 17 and nut 18, both 80 members of the stretcher are held in adjust- 85 ed position. The stretchers are relative in pairs and the members 14, 14' of each serve as bearings for rollers 19. Arranged on each pair of the rollers is a strickle-apron 90 20, its tension being determined by an ad- justment of the members of the relative stretcher, and said apron is moved on its rollers from time to time to bring new abrading surface thereof into operative po- 95 sition.

A strickle-board 21 may be substituted at times for a strickle-apron by clamping of its ends to the stretchers for the apron, said board being then forward of said apron, as 100 shown in Figs. 3 and 4. As a matter of de- tail the strickle-board has each end thereof provided with a right-angle bracket 22 that engages a member 14' of an apron-stretcher, and a set-screw 23 extends through said 105 bracket in opposition to said member of the stretcher. The slide aforesaid is shown as an angle-plate 24 having the down turned ends thereof engaged by the rods 6 of the guide-frame, and bolts extending through 110 the slide engage a longitudinal slot of an angular hanger-frame 25, the slotting of

said frame serving to provide for an adjustment thereof on the hanger. The ends of the hanger-frame are fashioned to engage side bars 26 of a traverse beam, that preferably comprises said bars and an intervening angular web 27 of sheet-metal riveted or otherwise suitably secured thereto, and said hanger-frame is provided with a slotted upper transverse member 25' central thereof, the slot being lengthwise of said frame-member. The hanger-frame herein specifically described is the traveler of the traverse-mechanism that is also herein specifically described, but the slide 24 may be connected, by suitable means, to the traveler of any other traverse-mechanism, particularly of the kind well known in the construction of various makes of card-grinding machines.

20 The traverse-mechanism herein shown and described comprises a link-belt 28 on suitably disposed sprocket-wheels for which the traverse-beam is provided with bearings, one of said wheels 29 being shown. This sprocket-wheel is put in bevel-gear connection with a spindle 30 for which the traverse-beam is provided with bearings 31 at one end thereof, and a pulley 32 is fast on the spindle to be driven by a belt.

25 30 A stem 33 in connection with a link of the belt 28 engages the slot of the transverse member 25', of the hanger-frame aforesaid and thus provision is had for automatically reversing the direction of travel of said frame and the strickle-mechanism therewith from time to time, there being a slide of said stem in said slot when the link of the belt therewith is turning on a sprocket-wheel.

35 40 By means of chains in connection with the traverse-beam, a bolt in pivotal connection with each chain engageable with an eye on said beam, and a thumb-nut runs on the bolt against said eye, the traverse-mechanism and the strickle-mechanism therewith may be fastened to the bearings of the fancy-roll of a carding-machine, and said strickle-mechanism adjusted to have the aprons thereof operate simultaneously upon the 45 card-clothing of the main cylinder and doffer of said machine, it being understood that said fancy-roll is removed and the strickle-mechanism suitably adjusted. In Fig. 2, one of the aforesaid chains 34, the bolt 35 there-50 with, an eye 36 on the traverse-beam, engaged by said bolt, and a nut 37 run on the aforesaid bolt is shown, and it is also shown in the same figure that the bearings 31 for the spindle 30 rest upon a fancy-roll bearing. In practice the other end of the traverse-beam will be suitably elevated on the other fancy-roll bearing.

55 60 For strickling other card-clothed carding-machine cylinders, the herein described traverse-mechanism may be attached to any

suitable stand organized for the support of one or two of such cylinders and the strickle-mechanism in connection with the traveler of said traverse-mechanism adjusted to operate upon one or both cylinders thus supported. 70

The guide-frame of the strickle-mechanism permits of continued movement on the part of the traverse-mechanism traveler subsequent to a stopping of said strickle-mechanism against a fancy-roll bearing or a standard of a supporting frame for the traverse-beam and a card-clothed cylinder or cylinder to be treated. 75

I claim:

1. A strickle-apparatus comprising a frame attachable to the traveler of a traverse-mechanism, an endless independently adjustable strickle-apron, and means whereby the apron is adjustable in connection with 80 said frame to various angles.

2. A strickle-apparatus comprising a frame attachable to the traveler of a traverse-mechanism, stretchers adjustable to various angles in connection with the frame, and a 85 strickle device in conjunction with the stretchers. 90

3. A strickle-apparatus comprising a frame attachable to the traveler of a traverse-mechanism, another frame in vertically adjustable connection with the one aforesaid, 95 arms in pivotally adjustable connection with the vertically adjustable frame, apron-stretchers similarly connected to the arms, rollers carried by the stretchers and an endless strickle-apron on the rollers. 100

4. A strickle-apparatus comprising a frame attachable to the traveler of a traverse-mechanism, another frame in vertically adjustable connection with the one aforesaid, 105 arms in pivotally adjustable connection with the ends of the vertically adjustable frame to extend therefrom in opposite directions, a stretcher pivotally adjustable in connection with each of the arms, rollers carried 110 by the stretchers, and endless strickle-aprons on the rollers.

5. A strickle-apparatus comprising a frame attachable to the traveler of a traverse-mechanism, another frame in vertically adjustable connection with the one aforesaid, 115 arms in pivotally adjustable connection with the vertically adjustable frame, stretchers similarly connected to the arms, and a strickle-device in conjunction with the 120 stretchers.

6. A strickle-apparatus comprising a guide-frame, a slide on the frame attachable to the traveler of a traverse-mechanism, a strickle-device, and means whereby the 125 strickle device is to various angles adjustable in connection with said frame.

7. A strickle-apparatus comprising a guide-frame, a slide on the frame adjustably attachable to the traveler of a traverse-mech- 130

- anism, a strickle-device, and means whereby the strickle-device is to various angles adjustable in connection with said frame.
8. A strickle-apparatus comprising a guide-frame, a slide on the frame, a hanger-frame to which the slide is connected, a beam upon which the hanger-frame is guided, a link-belt and sprocket-wheels therefor in conjunction with the beam, a stem extending from the belt in engagement with a slot of a transverse member with which said hanger-frame is provided, means for driving said belt, a strickle-device, and means whereby the strickle-device is to various angles adjustable in connection with said guide-frame.
9. A strickle-apparatus comprising a guide-frame, a slide on the frame, a hanger-frame to which the slide is connected, a beam upon which the hanger-frame is guided, a link-belt and sprocket-wheels therefor in conjunction with the beam, a stem extending from the belt in engagement with a slot of a transverse member with which said hanger-frame is provided, means for driving said belt, a pair of oppositely disposed endless independently adjustable strickle-aprons, and means by which the aprons are to various angles adjustable in connection with said guide-frame.
10. A strickle-apparatus comprising a guide-frame, a slide on the frame, a hanger-frame to which the slide is connected, a beam upon which the hanger-frame is guided, a link-belt and sprocket-wheels therefor in conjunction with the beam, a stem extending from the belt in engagement with a slot of a transverse member with which said hanger-frame is provided, means for driving said belt, a pair of oppositely disposed endless strickle-aprons on the rollers, and means whereby said stretchers are variously adjustable in connection with said guide-frame.

link-belt and sprocket-wheels therefor in conjunction with the beam, a stem extending from the belt in engagement with a slot of a transverse member with which said hanger-frame is provided, means for driving said belt, means for detachably securing the ends of said beam upon supporting devices, a strickle-device, and means whereby the strickle-device is variously adjustable in connection with said guide-frame.

11. A strickle-apparatus comprising a guide-frame, a slide on the frame, a hanger-frame to which the slide is connected, a beam upon which the hanger-frame is guided, a link-belt and sprocket-wheels therefor in conjunction with the beam, a stem extending from the belt in engagement with a slot of a transverse member with which said hanger-frame is provided, means for driving said belt, a pair of oppositely disposed stretchers, rollers carried by each stretcher, an endless strickle-apron on the rollers, and means whereby said stretchers are variously adjustable in connection with said guide-frame.

In testimony that I claim the foregoing I have hereunto set my hand at Milwaukee in the county of Milwaukee and State of Wisconsin in the presence of two witnesses.

WENDEL STOREY.
